J. Black,
Oscillating Steam Engine.
N° 23,524. Patented Apr. 5, 1859.

UNITED STATES PATENT OFFICE.

JAMES BLACK, OF PHILADELPHIA, PENNSYLVANIA, ASSIGNOR TO WORL BROTHERS, OF SAME PLACE; GEO. M. WORL ASSIGNOR TO WM. S. WORL.

STEAM-ENGINE.

Specification of Letters Patent No. 23,524, dated April 5, 1859.

To all whom it may concern:

Be it known that I, JAMES BLACK, of the city and county of Philadelphia, in the State of Pennsylvania, have invented a new 5 and useful Reciprocating Eccentric Revolving Steam-Engine; and I do hereby declare that the same is described and represented in the following specification and drawings.

The nature of my invention consists in 10 connecting one end of a piston rod to a hoop or hoops which revolve on fixed circles set eccentrically from the shaft, upon which the cylinder turns, in which said piston traverses.

15 To enable others skilled in the art to make and use my invention I will proceed to describe its construction and operation referring to the accompanying drawing, in which—

20 C, is a base supporting the stands K, K, which are firmly fastened to it, to support the trunnions B, B, of the cylinder A, upon which it turns; these trunnions may be extended beyond the stands to receive pulleys 25 or gears to communicate the power of the engine to the machinery which it is to operate. One of the trunnions B, is made large enough to contain the steam ways which supply the cylinder; the ways are made to receive the steam from the pipe H, which is in 30 the stand K, while the exhaust steam escapes at the pipe I, on the opposite side of the trunnion or shaft B, the shoulder of the enlarged portion of the trunnion being formed 35 with proper openings to receive and discharge the steam in a manner well known to mechanics.

The cylinder A is similar to those in common use except the trunnions above mentioned; and the piston rod is made to extend

through both of the cylinder heads, and has the piston fastened near its center, so that the rod traversing through both heads of cylinder, may always keep it in such a position that the piston will work freely. The 45 piston rod D, has a cross head E, at one end by which it is connected to the hoops, F, F, which turn on the rings G, G, or circles set eccentrically from the trunnions or shafts B, B, as shown in the drawing and fastened to the stands K, K; the steam ways being so arranged that when the cross head is nearest to the trunnions, the steam acts on the side of the piston farthest from the cross head, so as to force it from the trunnions and carries it around with the hoops F, F, to its greatest distance from the trunnion, changing the openings or ways in the shoulder of the journal, so as to let the steam act on the side of the piston next to the cross head and draw it toward the trunnions and thus keep the hoops turning on the rings or circles set eccentrically to the trunnions on which the cylinder turns.

I believe I have described and represented my invention so as to enable any person skilled in the art to make and use it.

I will now state what I desire to secure by Letters Patent, to wit:

The arrangement of the cylinder A, hoops 70 F, F, and disks or wheels G, G, when said disks are set eccentrically to an axle, which pierces the cylinder transversely, and one end of the piston rod of the cylinder is connected with and operates the hoops, substantially in the manner herein specified.

JAMES BLACK.
